CLAIM

The ornamental design for a toy turtle, as shown and described.

DESCRIPTION

FIG. 1 is a front elevational view of the toy turtle of the present invention, the rear view being a mirror image thereof;

FIG. 2 is a left side elevational view of the toy turtle of FIG. 1;

FIG. 3 is a right side elevational view of the toy turtle of FIG. 1;

FIG. 4 is a top plan view of the toy turtle of FIG. 1;

FIG. 5 is a bottom plan view of the toy turtle of FIG. 1; and,

FIG. 6 is a rear elevational view of an alternate embodiment of FIG. 1, the only difference being the removal of the cannon, the other views being the same.
